Primary Examiner — Susan M Lee*Assistant Examiner* — Linda G. Brooks(74) *Attorney, Agent, or Firm* — Dykema Gossett PLLC**(57) CLAIM**

The ornamental design for a light fixture with moving head, as shown and described.

DESCRIPTION

FIG. 1 is a front perspective view for a light fixture with moving head showing my new design;

FIG. 2 is rear perspective view thereof;

FIG. 3 is a front elevational view thereof, with the light fixture's head in an alternate position;

FIG. 4 is a rear elevational view of FIG. 3;

FIG. 5 is a left side elevational view of FIG. 3;

FIG. 6 is a right side elevational view of FIG. 3;

FIG. 7 is a top plan view of FIG. 3; and,

FIG. 8 is a bottom plan view of FIG. 3.

The broken lines showing elements of the lighting fixture in FIGS. 1-8 form no part of the claimed design.
